UNITED STATES PATENT OFFICE.

CHARLES G. NESSLER, OF NEW YORK, N. Y.

DESIGN FOR AN ELECTRIC HEATER FOR WAVING HAIR.

Application filed July 11, 1927. Serial No. 22,719. Term of patent 14 years.

To all whom it may concern:

Be it known that I, CHARLES G. NESSLER, a citizen of the United States, and resident of New York city, in the county of New York and State of New York, have invented a certain new, original, and ornamental Design for Electric Heaters for Waving Hair, of which the following is a specification, reference being had to the accompanying drawing, forming part thereof.

This application is a continuation in part of my application for design patent for electric heaters, Serial No. 16,517, filed February 18, 1926.

In the said drawings;

Figure 1, is a perspective view of the article showing my new design, also the color contrast between the handle and collar with the polished body portion and shank.

Figure 2, is a side elevation of the article. Figure 3, is an end elevation of the article. I claim:—

The ornamental design for an electric heater for waving hair, substantially as shown and described.

Signed at New York city, in the county of New York and State of New York this 8th day of July, A. D. 1927.

CHARLES G. NESSLER.
